Primary Examiner—James R. Largen*Attorney, Agent, or Firm*—Leon Gilden[57] **CLAIM**

The ornamental design for a toilet seat lifting handle, as shown and described.

DESCRIPTION

FIG. 1 is a front elevational view of the toilet seat lifting handle showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a perspective view thereof showing the lifting handle in use.

The broken line representation of a toilet, toilet seat and toilet seat cover in FIG. 7 is for purposes of illustration only and forms no part of the claimed design.

FIG. 1

FIG. 2

*FIG. 3**FIG. 4**FIG. 5**FIG. 6*FIG. 7
